United States Patent Office

Des. 184,096
Patented Dec. 16, 1958

184,096

PUFFED TEXTILE FABRIC

Douglas D. McCord, New York, N. Y., assignor to Chicopee Mills, Inc., a corporation of New York

Application September 27, 1957, Serial No. 47,888

Term of patent 14 years

(Cl. D92—1)

Fig. 1 is a plan view of a puffed textile fabric, showing my new design; and

Fig. 2 is an edge view.

I claim:

The ornamental design for a puffed textile fabric, as shown.

UNITED STATES PATENT OFFICE
CERTIFICATE OF CORRECTION

Design No. 184,096

December 16, 1958

Douglas D. McCord

It is hereby certified that error appears in the printed specification of the above numbered patent requiring correction and that the said Letters Patent should read as corrected below.

Column 1, line 2, after "design;" strike out "and"; line 3, for "Fig. 2 is an edge view." read -- Fig. 2 is a side edge view; and --; same column 1, between lines 3 and 4, insert the paragraph:

Fig. 3 is an end edge view.

Signed and sealed this 10th day of March 1959.

(SEAL)
